UNITED STATES PATENT OFFICE.

GEORGE F. PANZER, JR., OF BALTIMORE, MARYLAND.

ILLUMINATED AUTOMOBILE-TAG.

1,274,318.

Specification of Letters Patent. Patented July 30, 1918.

Application filed April 20, 1918. Serial No. 229,789.

To all whom it may concern:

Be it known that I, GEORGE F. PANZER, Jr., a citizen of the United States, residing at Baltimore, in the State of Maryland, have **5** invented new and useful Improvements in Illuminated Automobile-Tags, of which the following is a specification.

This invention relates to illuminated automobile tags and it consists in the novel features hereinafter described and claimed. **10**

An object of the invention is to provide a tag of the character stated which bears at its opposite spaces identification numbers and other matter as for instance the name **15** of the State in which the tag is issued and the year of its issue.

A further object of the invention is to provide upon the tag a light so arranged that the single light may illuminate the opposite side of the tag in a manner to make the reading matter at opposite sides of the tag clearly visible. **20**

With this object in view the tag includes a body having at its opposite sides the identification numbers and other matter and provided at its center with an opening. A light is arranged in the opening. This light may be a lamp or an electric bulb as desired. Approximately hemispherical shields are applied to the opposite sides of the body and inclose the light and the shields are provided with openings through which the rays of light may pass and fall upon the numbers and reading matter at the opposite **30** sides of the tag. The said shields are also provided with portions or sections which are impervious to the light rays and prevent the rays of light from spreading over those surfaces or areas of the tag which do not contain informational matter. The shields may **35** be provided at their central portions with lenses or different colored glass whereby the tag may also serve as a spot light placer or as a signaling means.

40 In the accompanying drawing:—

Figure 1 is a side view of the tag.

Fig. 2 is a transverse sectional view of the same.

The other figures are detailed views of **50** the features of the invention.

As illustrated in the accompanying draw-

ing the tag comprises a body 1 which may be of metal or any other suitable material and which bears at its opposite sides a number 2, name of the State 3 and the year 4 **55** in which the tag is issued.

The body 1 is provided at its center with an opening 5 which is adapted to receive a lamp 6. The lamp may be of an ordinary oil type or it may be in the form of an **60** electric bulb and it is so positioned within the opening that it will cast rays of light over the opposite sides of the body.

Hemispherical shields 7 are located at the opposite sides of the body 1 and are arranged to close over the opening 5. These shields may be hingedly connected with the body whereby the lamp or light may be inserted in the opening or removed therefrom at will. As these shields are alike a description of one will suffice. Each shield **70** 7 carries at its center a glass 8 which may be colored or which may be in the form of a lens. The shield 7 is provided with glass covered openings 9 some of which are arranged to permit the rays of light from the lamp to extend over the identification numbers, some to illuminate the name of the State and others to illuminate the year in **75** which the tag is issued. The material of the shield between the said openings and around the said glass is impervious to the rays of light consequently they prevent the plain portions of the surface of the body from being illuminated and the rays of **80** light which reflect from the inner surfaces of the said impervious portion eventually pass out through the openings and are cast over the reading matter upon the body of the tag. **85**

From the foregoing description taken in conjunction with the accompanying drawing it will be seen that an automobile tag of simple and durable structure is provided and that the same is provided with means **90** 95 whereby a single light may illuminate the opposite sides of the body of the tag and also the rays of light will be conserved inasmuch as they will not be spread over the plain portions of the tag but will be concentrated over those portions which bear the identification numbers or data. **100**

Having described the invention what is claimed is:

A tag comprising a body having an opening and provided at its opposite sides with identification data, a light located in the opening and arranged to cast its rays over the data at the opposite sides of the body, shields located over the light and having

openings through which the rays may pass to the data, the said shields also being provided with portions impervious to light which will cut off the rays from the light to those portions of the tag which are plain. ¹⁰

In testimony whereof I affix my signature.

GEORGE F. PANZER, JR.
